FISHING PLUG

George E. Ross, St. Paul, Minn., assignor of a fractional part interest to Francis R. Drake, Minnetonka, Minn..

Filed May 24, 1971, Ser. No. 146,598

Term of patent 14 years

Int. Cl. D22—05

U.S. Cl. D22—27

FIG. 1.

FIG. 4.

FIG. 2.

FIG. 5.

FIG. 3.

FIG. 1 is a top view of a fishing plug embodying my new design;

FIG. 2 is a right side elevation view of the fishing plug; the left side elevation view being a mirror image of the same;

FIG. 3 is a bottom view of the same;

FIG. 4 is a front elevation view of the same; and

FIG. 5 is a rear elevation view of the same.

I claim:

The ornamental design for a fishing plug, as shown and described.
